SHAMPOO DISPENSING BRUSH

Opal G. Hamm, 104 Skippack Pike, Center Square, Pa.

Filed Nov. 19, 1963, Ser. No. 77,495

Term of patent 3½ years

(Cl. D9—2)

FIG. 1 is a top plan view of the shampoo dispensing brush embodying my new design;

FIG. 2 is a bottom plan view of the shampoo dispensing brush shown in FIG. 1;

FIG. 3 is a side elevational view of the shampoo dispensing brush shown in FIGS. 1 and 2; and

FIGS. 4 and 5 are transverse sectional views taken substantially on lines 4—4 and 5—5 of FIG. 2, respectively.

The dominant features of my design reside in the portions shown in full lines.

I claim:

The ornamental design for a shampoo dispensing brush, as shown and described.
